DOWEL BAR AND EXPANSION JOINT STRIP HOLDER

Joseph William Heltzel, Warren, Ohio

Application April 10, 1935, Serial No. 15,714

7 Claims. (Cl. 94—51)

The present invention relates to a device for use in road building and the like, and has for an object to provide a portable holder or frame which will hold in proper relative positions a number of dowel or reinforcing bars and will also hold an expansion joint strip in proper relation to the bars so that the holder or frame may be bodily placed on the subgrade of a road, the road material filled in about the bars and joint strip and the holder then released from the bars and strip and withdrawn from the filled-in road.

Another object of this invention is to provide a frame or holder with means for releasably holding or locking the dowel bars and the joint strip on the holder and in proper relative positions, so that the organization may be set up at one side of the road or on the road bed itself and may then be transferred and adjusted into proper position for holding the strip and the bars in their final positions during the pouring or filling in of the road material, and wherein the frame may be released from the strip and the bars and withdrawn from the filled-in material without disturbing the positions of the strip and bars so that they may remain in their final positions.

The invention also provides an improved structure of frame which may be used in multiple or may be repeatedly used and which supports the longitudinal bars in such relation to the frame that the bars may be overlapped to the desired extent to effect the necessary reinforcement in the finished road slabs or body.

The invention also aims at certain detail and novel structural features to provide a frame or holder which is of skeleton form to admit the road material thereabout and therethrough and which is strong and durable and provided with operating means easily accessible from the upper side or part of the frame.

Another object of the present invention is to provide a frame with a single locking and releasing device which will operate on both the bars and the expansion joint strip so as to simultaneously lock the same to the frame for transportation and adjustment with the frame and which may be operated to simultaneously release both the bars and the strip when the frame is to be removed therefrom.

A further feature of the present invention is to provide an improved reinforcing and holding means for the expansion strip which may be removed with the frame, or which may remain in engagement with the expansion joint strip after the frame is removed for reinforcing and protecting the strip against injury and distortion inci-

dent to the screeding of the road material by the finishing machine passing over the road.

With the foregoing and other objects in view, the invention will be more fully described herein-after, and will be more particularly pointed out in the claims appended hereto.

In the drawings, wherein like symbols refer to like or corresponding parts throughout the several views,

Figure 1 is a top plan view of a combined dowel bar and expansion joint holder showing the expansion joint strip and the dowel bars in position thereon.

Figure 2 is a side elevation of the same.

Figure 3 is a longitudinal section taken through the holder on substantially the line 3—3 of Figure 1.

Figure 4 is an end elevation of the holder, showing the joint strip brace and carrier locked to the holder.

Figure 5 is a transverse section taken on the line 5—5 of Figure 1 through the intermediate portion of the holder.

Figure 6 is a detail perspective view of one of the cross braces or members of the holder, and

Figure 7 is a fragmentary perspective view of one end of the locking and releasing means for both the strip and the dowel bars.

Referring now to the drawings, the frame or body portion of the holder comprises a pair of side strips 15 which are of suitable length, which are of the desired depth to give stability to the frame and which are disposed edgewise in a vertical position and held in substantially parallel spaced apart relation by cross pieces 16.

As shown in Figure 6 particularly, each cross piece 16 may comprise a sheet metal plate having right angularly turned flanges 17 at opposite ends suitably apertured near their upper edges for the reception of rivets 18 or the like which also pass through the adjacent portions of the side strips 15 for holding the flanges 17 against the inner sides thereof. Each flange 17 is provided at its lower edge, and preferably adjacent the body of the cross piece 16 with a downwardly opening slot or seat 19 for the reception of a transversely disposed dowel or cross bar 20 adapted to be held to the under side of the frame. These seats 19 insure the desired transverse alignment of the dowel bar 20 in the under side of the frame.

The intermediate or central portion of the cross piece 16 is provided with a downwardly opening slot 21 adapted to receive therein an expansion joint strip 22 which may be constructed of asphaltic material, or other suitable ma-

aterial adapted to provide an expansion joint between adjacent road slabs or sections. The slot 21 opens at its upper end into an enlarged cavity or recess 23 suitably proportioned and shaped to receive and guide certain devices hereinafter described. The dowel or cross bars 20 are adapted to be mounted in multiple upon the frame or holder, as shown in Figure 1, and it is preferable to space these dowel bars 20 apart lengthwise of the frame at relatively short distances which, for example, may be placed at one foot apart. It is inadvisable to provide a cross piece 16 at each dowel bar 20, therefore, on account of the additional weight of the holder or frame and because such additional strengthening of the holder is not required. For this reason the side strips 24 are provided, intermediately of the cross pieces 16, with depending seat plates 24 which are riveted or otherwise suitably secured to the inner sides of the strips 15 and which extend downwardly a distance equal substantially to that of the flanges 17 and are provided in their lower ends with similar downwardly opening seats or slots 19.

25 Provision is thus made for supporting the intermediate cross bars 20, and all of the seats 19 are of substantially the same height with respect to the lower edges of the frame.

The frame is adapted to carry longitudinal dowel bars 25 at opposite sides, and these dowel bars are disposed across the under sides of the opposite end portions of the dowel cross bars 20 so that the latter are held up in their seats 19 by the longitudinal bars 25 when the latter are held in raised position. The seats 19 thus provide means for limiting the upward movement of all of the dowel bars so as to hold the same at the desired height on the frame which is determined by the depth to which the dowel bars are to be embedded in the finished road structure.

Each cross piece 16 is provided with a pair of holding arms 26 which are substantially of bell crank construction and are mounted at their angle portions upon pivots 27, which may be bolts, rivets or the like, carried upon the cross piece 16 at opposite sides of the recess 23. The arms 26 have their shorter portions directed toward the slot 21 so that they approach but effectively clear the opposite sides of the expansion joint strip 22 when the latter is disposed in the slot 21. The longer portions of the arms 26 extend downwardly and outwardly of the frame and project through the seats or slots 19 at the sides of the frame and have upturned shoulders 55 or fingers 28 adapted for engagement beneath the longitudinal bars 25 to raise the same as the outer ends of the arms 26 are swung upwardly so as to raise the dowel bars 25 and 20 into their upper positions on the frame. It will be noted, 60 particularly from Figure 5, that the premolded asphaltic joint strip 22 is provided with openings 29 therethrough for the reception of the intermediate portions of the cross dowel bars 20. This is for the purpose of obtaining the desired 65 relation between the dowel bars and the joint strip and at the same time to hold or raise the joint strip 22 with the cross or transverse dowel bars 20 under the action of the arms 26. The inner or shorter ends of the arms 26 extend substantially horizontally inward at their free ends and engage pairs of cams 30 which are slidably disposed through the recess 23 of the cross piece 16.

As shown particularly in Figure 7, each pair 75 of cams may comprise the downturned sides of

U-shape shoes or cam members which may be constructed of sheet metal and which may be creased at its upper intermediate portion for mounting over a shiftable operating rod 31 which also extends through the recess 23 of the cross piece 16.

This rod 31 is continued throughout substantially the length of the holder or frame and passes through each of the cross pieces 16, and is provided at each cross piece with one of the double cams 30 so as to operate simultaneously and equally upon each pair of arms 26. The cams 30 are of suitable length so as to gradually swing the arms 26 as the cams are shifted, and all of the cams 30 are inclined in one direction 15 and are relatively positioned on the rod 31 so as to move therewith for successively bringing into operation the corresponding points on all of the cams. The block or projection 32 is fixed upon the rod 31 at a suitable point, preferably at the 20 rear end of one of the double cams 30, so that this block or projection 32 may strike the adjacent cross piece 16 and constitutes a stop for limiting the releasing movement of the rod 31 with its cams.

A protecting plate 33 is provided for engagement along one side of the expansion joint strip 22 to hold the same to shape, and this protecting strip 33 has slots 34 therein extending downwardly from the adjacent openings 29, so that the protecting plate 33 may be slid upwardly from engagement with the transverse dowel bars 20 at times. The upper end of the protecting plate 33 is turned over to provide a cap 35 adapted to embrace the upper end portion of the strip 22 and 35 the cap 35 may have openings therethrough for the reception of detachable nails or pins 36 used for holding the strip 22 in the cap and against one side of the protecting plate 33.

The double cam 30 is U-shape and opens 40 downwardly to receive the cap 35 and the upper end of the strip 22 and also for the purpose of carrying, at one side of the operating rod 31, an inwardly swinging hook 37 proportioned to engage beneath the free edge portion of the cap 45 35 at one side of the strip 22, so as to hold and support the strip 22 with the protecting plate 33 directly from the frame structure.

It will be noted from Figures 1, 2 and 3, that the side strips 15 of the holder frame are of less 50 length than that of the longitudinal dowel bars 20 and are of substantially V-length of the joint strip 22 with its protecting plate 33 and cap 35. This proportioning of parts is provided so that the longitudinal dowel bars 25 may be success- 55 sively overlapped in the road structure, particularly when a number of the holding devices are disposed end to end. With this structure when the frame is removed from one set of bars and joint strip it may be positioned in the road with 60 a second set of bars and strip thereon in end- 65 wise relation to the prior embedded bars and strip. This provides for a continuous overlapping of the longitudinal bars and the disposing of the joint strips 22 in endwise abutting relation throughout the length of the road structure.

In use, the operating rod 31 is retracted to its full extent so as to release the arms 26 and allow them to swing inwardly out of, or substantially out of, the seats 19. The arms 26 are flat and are 70 braced flat against the side of the cross piece 16 so that the arms move substantially in a common transverse plane. The cross dowel bars 20 are now placed in the seats 19 above the longitudinal bars 25 and the latter are engaged with the fin- 75

gers 28 of the arms 26 when the operating rod 31 may be driven or otherwise moved toward the operating position. This operative movement of the rod 31 brings the outer cams into sliding contact across the inner ends of the arms 26, forcing the inner ends downwardly and swinging the outer ends or fingers 28 upwardly against and with the longitudinal dowel bars 25 and the transverse dowel bars 20. When the bars are raised in the seats 19 to the desired extent, the cams 30, being of a gradual slope, provide frictional locking means for holding the bars in raised position. In placing the transverse bars 20 in the seats, the bars 20 are engaged through the openings 29 in the joint strip 22 so that the latter is moved up into position as the bars are raised and the hook 37 has an inclined lower face adapted to slide over the cap 35 and permit the hook to latch beneath the free edge of the cap 22 to support the protecting plate 33 with the strip 22 from the central portion of the holder.

The holder with the bars and strips thereon may be set up immediately upon the subgrade, or at one side of the road and then transported in the proper position on the subgrade. The road material is filled in about the frame and the bars and against the joint strip 22, and when conditions permit, the frame may be withdrawn from the strip and the bars to leave them in proper position embedded in the roadway material. When the frame is to be released, the operating rod 31 is shifted, by impact of a shovel or other suitable tool or implement against the block 32 into position to retract the cams 30 from the arms 26. When the cams are fully retracted, the hooks 37 may be swung upwardly out of engagement with the cap 35 and the frame then lifted. The weight of the rods 25 and 20 together with the drag of the settled road material thereabout, swings the outer ends of the arms 26, if freed from the cams 30, downwardly so as to release the rods and the joint strip 22 from the frame. The frame may now be raised out of the road material and the joint strip and the dowel bars may be left in their proper relative positions embedded in the road material. It will be noted that in this operation the protecting plate 33 has been left in engagement with the expansion joint strip 22 so that the latter is protected against distortion incident to screeding and other operations upon the road.

After the operation on the road material the pins or nails 36 may be withdrawn from the cap 35 and the latter with the protecting plate 33 may be raised out of the road material so as to leave the joint strip in proper position therein. On the other hand, if desired, before the frame or holder is removed from the road material, the hooks 37 may be swung downwardly and when locked with the cap 35 and the pins 36 may be either left out of the cap 35 or withdrawn before the road material is entirely filled in thereabout. When the frame is lifted the cap 35 with the protecting plate 33 is withdrawn from the joint strip 22 and the transverse dowel bars 20.

Of course in case the cap strip 35 is to be removed at all times with the body or main frame by certain contractors, in such case the cap strip 35 may be fastened integrally to the cross piece 17 of the frame preferably by welding the plate 33 at the margin of the slots 21. Thus the cap strip 35 and the supporting plate 21 may be used practically as a part of the main frame itself. The latch 37 may be omitted in this instance, but may of course be used when the protecting plate

33 and the cap 35 are detachable from the frame.

As shown in Figure 4, in order to properly space the frame with the dowel bars 20 and 25 thereon from the side form 38 of the roadway, a spacing bar 39 of suitable length is used. This spacing bar 39 has sockets 40 and 41 at opposite ends which open downwardly and respectively engage over the upper edge of the side strip 15 of the body frame and the upper edge of the side form 38. This insures the correct positioning and alinement of the dowel bars in the finished road structure.

What is claimed is:—

1. In a dowel bar and expansion joint strip holder, a frame having a cross piece therein, said cross piece having an intermediate slot opening through the lower edge thereof to receive a joint strip therein, said cross piece having a recess at the upper end of said slot, said frame having transversely alined seats for receiving cross bars therein, longitudinal bars disposed at opposite sides of the frame, a pair of arms pivotally mounted on the cross piece with outer ends for engaging the longitudinal bars to support the same and said transverse bars in the seats, and a double cam slidably disposed in said recess of the cross piece with cam portions in sliding contact with the upper ends of said arms for operating the same upon the shifting of the double cam.

2. In a dowel bar and expansion joint strip holder, a cross piece having a vertical slot therein for receiving a joint strip and having a recess opening into the slot at the upper end of the latter, a pair of bar engaging arms pivotally mounted on the cross piece and having inner ends extending toward said recess, and a double cam disposed in said recess adapted to bridge the upper end of the joint strip and said recess being shaped to the exterior configuration of the cam for holding and guiding the same for movement through the recess, said cam adapted at opposite sides to engage the said inner ends of the arms.

3. In an expansion joint strip holder, a frame having a cross piece therein, said cross piece having a vertical slot for the reception of a joint strip, a protecting plate removably disposed in the slot and having a cap at its upper end, said plate and cap adapted to engage against one side and about the upper edge of a joint strip to reinforce and support the same during pouring and partial setting of road material, and a latch carried by said cross piece detachably engaging the cap to remove the same and the plate from the joint strip when embedded in the road material.

4. A holder as specified, comprising a frame having a cross piece with a vertical slot therein for the reception of a joint strip, a cam slidably disposed through the upper portion of the cross piece and the latter having a cam receiving recess of the configuration of the cam for guiding and supporting the same, operating arms pivotally mounted on the cross piece at opposite sides of the cam and having upper ends disposed in the path of the cam, a protecting plate for engagement against the side of a joint strip and having a cap at its upper end for engagement over the upper edge of the joint strip, means for detachably securing the joint strip to the cap, and a latch carried by said cam for detachable engagement with said cap for coupling the same together with the joint strip to said frame.

5. In a dowel bar and expansion joint strip holder, a frame having a plurality of transversely

aligned seats along the sides of the frame opening downwardly and adapted to receive transverse dowel bars therein, said transverse dowel bars adapted to receive longitudinal dowel bars across 5 their lower sides, pairs of arms mounted in the frame adapted to engage at their lower ends beneath the longitudinal dowel bars, double cams mounted on the frame for engaging the arms to actuate the same and lift said bars, and joint 10 strip engaging means detachably connected to said cams for supporting a joint strip in position relative to said bars.

6. In a dowel bar and expansion joint strip holder, a frame, individual dowel bar carrying 15 means on the frame, an expansion joint strip protecting plate for engagement against the side of a joint strip and having a cap portion at its upper edge detachably connected to the strip, and a single releasable device movable along the 20 frame for engaging said cap portion of the plate and said individual dowel bar carrying means for suspending dowel bars and the joint strip in the

frame and for quickly and simultaneously releasing the same.

7. A portable holder for dowel bars and expansion joints, comprising a channeled central member extending longitudinally of the holder 5 and opening downwardly for receiving a joint strip therein, means for holding the joint strip in the channeled member, a plurality of spaced apart transversely disposed cross pieces mounted on the channeled member, side plates secured 10 across the ends of the cross pieces in spaced relation at opposite sides of the channeled member and having rod receiving sockets in their lower edges, means for holding dowel bars in said sockets and in crossed relation on the side plates, 15 and a single operating means connected to the joint strip and bar holding means for admitting simultaneous release of the joint strip and the dowel bars from the holder for withdrawal of the latter. 20

JOSEPH WILLIAM HELTZEL.
